UNITED STATES PATENT OFFICE

SOLOMON TEPLLOW, OF LOS ANGELES, CALIFORNIA

TELEPHONE BOOTH

Application filed August 23, 1926. Serial No. 131,078.

My invention relates to telephone booths of the character embodied in my co-pending application Serial No. 52,191, filed August 24, 1925, in which a booth is designed to enclose only the upper half of the human figure.

It is a purpose of my present invention to provide a booth of the above described character which includes a body of any general shape desired best suited to a particular location in a room and having an entrance and exit opening which is confined wholly within the area of the body when in both open and closed positions, thus reducing the over-all area of the booth to economize space, simplifying its construction, and thereby reducing the cost of manufacture, and enhancing its artistic appearance.

It is also a purpose of my invention to provide a telephone booth which affords to a superior degree the property of excluding extraneous sounds in booths of this character, and one which provides a supporting means upon which packages, books, etc., can be placed while telephoning.

I will describe only four forms of telephone booths embodying my invention and will then point out the novel features thereof in claims.

In the accompanying drawings,

Figure 1 is a view showing in perspective a telephone booth embodying my invention with the door thereof in partly closed position;

Figure 2 is a horizontal sectional view of the booth shown in Figure 1;

Figure 3 is a view similar to Figure 2, showing another form of telephone booth embodying my invention;

Figure 4 is a view similar to Figure 3, showing a third form of telephone booth embodying my invention;

Figure 5 is a view showing in front elevation a fourth form of telephone booth embodying my invention with a portion thereof broken away;

Figure 6 is a horizontal sectional view of the booth shown in Figure 5, the door being in closed position and the open position indicated in dot-and-dash lines.

Similar reference characters refer to similar parts in each of the several views.

Referring to the form shown in Figures 1 and 2, the booth, in its present embodiment, is of circular form in cross section, it being made up of an annular side wall 15 closed by a top wall 16, while the bottom of the booth is open. The side wall 15 is of split annular form to provide a side opening 17 through which access is had to the interior of the booth. Within the booth is a partition 18 constituting a shelf. This shelf is located adjacent the bottom of the booth body, so as to partly close the bottom. It is preferably made in the form shown in Figure 2, and its inner or free edge is curved reversely with respect to the curvature of the front portion of the side wall.

It will be noted that the opening 17 communicates at its lower end with the open bottom of the booth body, in order that a person using the booth may enter or leave the latter through such opening, it being understood that the over-all length of the booth is such as to enclose only the upper half of the human figure, and it will be further understood that the booth is adapted to be supported in elevated position with respect to the floor. This opening 17 is adapted to be closed by a door 19 having a transverse curvature corresponding to that of the curvature of the side wall 15, so that when in closed position, as shown in Figure 2, it forms a continuation of the side wall and thus co-operates with the inner edge of the shelf 18 to form interiorly of the booth an ovate bottom opening in which the user of the booth is adapted to stand when telephoning. The partition 18, as previously mentioned, partly closes the bottom of the booth and thus functions to exclude extraneous sounds. In addition it provides a support upon which packages, books, etc., can be placed while a person is telephoning.

The door 19, in the present instance, is mounted for sliding movement at one side of the side wall 15, door guiding and supporting members 20 being secured to the side wall to slidably receive the upper and lower edges of the door and in a manner to permit the

door to be moved to open or closed position, as will be understood.

Referring now to Figure 3, I have here shown another form of booth embodying my invention which is similar in construction to the booth shown in Figure 1 in that it is provided with a closed top and an open bottom. The body of the booth is provided with a straight vertical back wall 21, and side walls 22 extend at right angles from the vertical edges of the back wall. The side walls 22 are curved at their forward portions to provide a curved front wall 23 having an opening 24 functioning in the same manner as the opening 17 and adapted to be closed by a door 25 constructed and mounted in the same manner as the door 19. The booth is interiorly provided with a shelf 26, the inner edge of which is curved reversely with respect to the curvature of the front wall 23 to provide an ovate opening at the bottom of the booth.

Referring now to Figure 4, I have here shown a third form of booth embodying my invention in which the booth body is of rectangular form having a back wall 27, side walls 28, and a front wall 29 provided with an opening 30 adapted to be closed by a door 31. The door 31 is straight to form, when in closed position, a continuation of the front wall 29, and this door is slidably mounted in guiding and supporting members 32, in order that it may be slid to open or closed position.

In Figures 5 and 6, I have shown another form of booth embodying my invention which comprises a back 33, straight sides 34 spaced to provide an entrance and exit opening, the sides and back being connected at their upper ends by a top 35. The opening provided between the side walls 34 is adapted to be closed by a door 36 transversely curved as shown in Figure 6, and hingedly supported to one side, as indicated at 37, so as to swing to the closed position shown in solid lines and to the open position shown in dot-and-dash lines. This door when in closed position spans the space between the forward and vertical edges of the sides 34, and by virtue of its curvature produces a rounded effect to the front of the booth. Within the booth and secured to the back and side walls is a partition or shelf 38, the free edge of which is curved reversely with respect to the door 36, so as to co-operate with the latter in providing an ovate opening at the bottom of the booth. Similarly, the shelf 38 functions to exclude extraneous sounds, but sufficient space is provided between the shelf and the door to accommodate the person using the telephone.

In all forms of my invention, the doors may be provided with a window 39, through which it may be observed when the booth is occupied.

Although I have herein shown and described only four forms of telephone booths

embodying my invention, it is to be understood that various modifications may be made therein without departing from the spirit of the invention and the spirit and scope of the appended claims.

I claim as my invention:

1. A telephone booth comprising a section open at one side, closed at its top and formed at its bottom with a shelf, and a door structure forming the only other section of the booth and supported entirely from said first section and arranged when closed to coact with the shelf to permit the body of a person when standing to be accommodated in the space between the door and said shelf so that the portion of the body above the waist will extend into the booth. 70

2. A telephone booth comprising a section open at one side, closed at its top and formed at its bottom with a shelf, and a door structure forming the only other section of the booth and supported entirely from said first section and arranged when closed to coact with the shelf to permit the body of a person when standing to be accommodated in the space between the door and said shelf so that the portion of the body above the waist will extend into the booth, the said shelf serving to exclude extraneous sound from the booth by way of the bottom thereof. 80

3. A telephone booth comprising a section open at one side, closed at its top and formed at its bottom with a shelf, and a single door forming the only other section of the booth and arranged when closed to coact with the shelf to form an intervening space for the accommodation of the body of the person using the booth so that all of the body above the waist line will be enclosed within the booth, the said shelf serving to exclude extraneous sound from the booth by way of the bottom thereof. 90

4. A telephone booth comprising a section open at its bottom, closed at its top and formed at one side with a vertical opening, and a horizontally swinging closure for said side opening adapted to be directly operated by hand respectively from within and without the booth. 100

5. A telephone booth comprising a walled section open at its bottom and provided at its top with a roof, and a door associated with said section in operative movable relationship thereto and adapted to assume a vertical position directly under the roof when the door is closed, and to coact with the walls of said section to constitute therewith a complete enclosure about the body of the user from the head to approximately the waist-line. 110

6. A telephone booth comprising a walled section open at its front and at its bottom, enclosed at its top by a roof, and an outwardly curved door movably hung upon the 120

section and adapted when closed to cover the open side of the section and to co-act with all of the walls of the section so that and therewith to circumscribe the body of the user
5 from a point at the head down approximately to the waistline.

SOLOMON TEPLow.
